UNITED STATES PATENT OFFICE.

OSCAR F. PETERSON, OF KEOKUK, IOWA.

JAR-HOLDER.

945,589.

Specification of Letters Patent.

Patented Jan. 4, 1910.

Application filed February 8, 1909. Serial No. 476,587.

To all whom it may concern:

Be it known that I, OSCAR F. PETERSON, a citizen of the United States, and a resident of Keokuk, in the county of Lee and State 5 of Iowa, have invented a new and Improved Jar-Holder, of which the following is a full, clear, and exact description.

This invention relates to jar holders, and more particularly such as each of which includes a frame adapted to be arranged on a receptacle, and means for removably securing the frame in place.

The object of the invention is to provide a device of the class described, simple and 15 serviceable in construction and inexpensive to manufacture, which can be easily mounted on a receptacle, such as a pan or the like, and which serves to hold a number of preserve jars in place while the latter are being 20 filled.

Reference is to be had to the accompanying drawings forming a part of this specification, in which similar characters of reference indicate corresponding parts in both 25 figures.

Figure 1 is a perspective view of an embodiment of my device, showing a number of preserve jars held in place; and Fig. 2 is a plan view of the frame.

Before proceeding to a more detailed description of my invention, it should be understood that in filling jars with preserves, the heat of the latter often causes the jars to crack. To avoid this I have provided a 30 frame which can be readily mounted on a pan or other receptacle, and which has means for holding a plurality of preserve jars in place. When the jars are to be filled, some warm water is poured into the receptacle, and in this way the jars become 35 slightly warm, so that the heat from the preserves as they are poured in will not crack the jars.

In the specific form shown in the drawings, 1 represents a receptacle of common 45 form and provided with a laterally-disposed rim 2. Adapted to be arranged upon the receptacle is a frame 3 formed of any suitable material such as sheet metal, wire or the like, 50 and having a plurality of openings 4 cut therein. When the device is in operation, these openings serve to receive the preserve jars which are to be filled. The frame 3 is further provided with a plurality of arms 5, 55 having downwardly-disposed lugs 6. The latter serve to engage the rim 2 of the re-

ceptacle, as shown most clearly in Fig. 1 of the drawings. A further arm 5^a is bifurcated. Adapted to be arranged at this arm is a slidable extension 7 having a lug 8 60 adapted to engage the rim 2 of the receptacle. Mounted on this extension and adapted to slide between the bifurcated sides of the arm is a threaded stem 9. A butterfly or wing nut 10 engages the threaded stem 65 9 and serves to lock the extension 7 in place.

In the operation of the device, the frame 3 is arranged on a receptacle as shown in Fig. 1 of the drawings, the lugs 6 of the arms 5 engaging the rim of the receptacle. By 70 means of the extension 7 the frame can be arranged on receptacles of different sizes, the nut 10 serving to lock the extension in place after the lug 8 has engaged the rim of the receptacle.

It should be understood that I do not limit myself to the specific form shown in the drawings, as others equally advantageous may be employed without departing from the spirit or the scope of the invention. 75 80

Having thus described my invention, I claim as new and desire to secure by Letters Patent:

1. In a device of the class described, a frame having a substantially circular body 85 portion, provided with a plurality of circular openings extending through the same and adapted to receive preserve jars, spaced arms projecting from the periphery of the body portion of the frame and provided with 90 means for engaging the rim of a receptacle, an arm also projecting from the periphery of the body portion of the frame and having a slidable extension provided with means for engaging the rim of the receptacle, and a 95 locking device for said slidable extension.

2. In a device of the class described, a frame provided with a plurality of arms, 100 said arms having downwardly disposed lugs adapted to engage the rim of a receptacle, said frame also having a bifurcated arm and having a plurality of openings extending through the frame, adapted to receive preserve jars, adjustable extensible means for securing said frame on a receptacle, said 105 means consisting of a slidable extension having a lug adapted to engage the rim of the receptacle, a threaded stem on said extension and slidably fitting between the members of said bifurcated arm, and a butterfly nut engaging the threaded stem to lock said extension to said bifurcated arm of said frame. 110

3. In a device of the class described, a frame having a central opening and a plurality of openings arranged in a circle around the central opening, arms on said frame having means for engaging the rim of a receptacle, said frame also having a bifurcated arm, an adjustable extension having a member slidably fitting between the members of said bifurcated arm, the said extension being 5 also provided with means for engaging the 10 rim of a receptacle, and means for locking the said extension to said bifurcated arm.

In testimony whereof I have signed my name to this specification in the presence of two subscribing witnesses.

OSCAR F. PETERSON.
